RADIO APPARATUS

Clarke Bond, Los Angeles, Calif.

Application April 17, 1931. Serial No. 530,976

1 Claim. (Cl. 250—20)

This invention relates to improvements in radio apparatus and has particular reference to a program and station selector.

The principal object of this invention is to provide means for automatically turning on a radio program being broadcasted forming any one of a selected group of broadcasting stations.

Another object of the invention is to produce a device which may be employed with any standard radio receiving set now in use.

A further object is to produce a device of this character which is simple in construction and one which may be actuated by any member of the household.

15 A still further object is to produce a device which is economical to manufacture.

Other objects and advantages will be apparent during the course of the following description.

In the accompanying drawings forming a part 20 of this specification and in which like numerals are employed to designate like parts throughout the same,

Figure 1 is a diagrammatic wiring diagram,

25 Figure 2 is a fragmentary detail view of the stop gate mechanism,

Figure 3 is a fragmentary front elevation showing the relay of adjustable knobs,

Figure 4 is a fragmentary view taken on the line 4—4 of Figure 5,

30 Figure 5 is a horizontal cross sectional view showing certain parts in elevation,

Figure 6 is a front elevation of the clock mechanism,

Figure 7 is an enlarged fragmentary detail 35 view of two of the selector keys,

Figure 8 is an enlarged detail side elevation partly in cross section showing one of the selector keys during its engagement with the hour hand,

40 Figure 9 is a side elevation of one of the selector keys in set position,

Figure 10 is a fragmentary rear elevation of the clock connections, and

45 Figure 11 is an end elevation of the stop gate taken on the line 11—11 of Figure 5.

It is often desirable to select from a broadcast program several features which would be entertaining and desirable to listen to. Up to the present time it has been necessary, as far as applicant is aware, to select from the program those stations desired and then to manually turn on the radio at the designated hours and to tune the radio set to the station from which the particular program is emanating. It often therefore occurs that a person misses a program

through inadvertently forgetting to turn on the radio receiving set or through the fact that a person may be located in another room and unable to reach the radio as is often the case with invalids.

With my apparatus it is possible to select the program desired from any one of the number of stations and to have the radio receiving set automatically turn on this station at the proper time. The apparatus will operate over a period 65 of twelve (12) hours and it is of course obvious that by using a twenty-four (24) hour clock, the set could be caused to operate over that period.

In the accompanying drawings wherein for the purpose of illustration is shown a preferred 70 embodiment of my invention, the numeral 5 designates the face of a clock, which clock may be driven in any convenient manner as for instance by a spring or by being electrically connected to the customary house circuit. This 75 clock has an elongated hour hand 6 which hour hand extends over a plurality of concentric insulated rings 7, these rings 7 being insulated from each other each insulation as best shown in Figure 7 and designated by the numeral 8. Mounted 80 on each ring is a plurality of pivoted contacts 9 each of which has an arm 11, the shaft of the contacts being made of insulation. Each of the concentric rings is electrically connected by wires (see Figure 10) to a remotely positioned relay 85 and the elongated portion 6 of the hour hand is electrically connected to the opposite side of the circuit so that when this hour hand comes into engagement with one of the arms 11, a circuit will be completed to the relay belonging to 90 the particular ring in which the arm is located, and the action of this relay will be later described.

Referring now to Figures 4 and 5 it will be noted that a motor is shown at 12 which motor is geared to a wheel 13 which in turn is adapted 95 to drive a wheel 14 to which wheel a crank 16 is pivoted. This crank is in turn pivoted as at 17 to a wheel 18. This wheel 18 may be connected in any convenient manner to the tuning mechanism of the radio set and is mounted upon a shaft 19 which extends through the panel 21 and has a knob 22 thereon. This knob is connected by a link 23 to a pivoted arm 24 which is in turn connected by a link 26 to the clutch mechanism 27 mounted in the wheel 13, the purpose of which is to provide means whereby by pulling outwardly on the knob 22 the clutch 27 may be actuated for releasing the wheels 13 and 14 so that the set may be manually actuated when desired. A pull rod 28 is pivoted to the pivot 110

point 17 and to the traveller 31 which moves between the tracks 32. This traveller carries a stop gate which consists of a pair of arms 33 and 34 to which pivoted ends 36 and 37 respectively are attached. These pivoted ends each carry an insulating strip as shown at 38 and 39 the purpose of which will be later seen. Springs not shown serve to keep the pivoted ends in alignment with the arms.

10 Referring now to Figure 3, it will be noted that a series of slots 41 are formed in the panel 21 and serve to position a plurality of knobs 42 to each of which is connected an electrical relay 43. This relay carries a stop 40 which may be moved into alignment with the pivoted ends 36 and 37 of the gate. This relay 43 has one end electrically connected to one of the rings 7 and has its opposite end connected to a motor relay 44, the opposite end of which is connected to the transformer wire 46, the transformer being shown at 45. The opposite side of the transformer is connected by a wire 47 to the clock 5 and consequently the hand 6. The motor relay 44 is adapted to actuate a switch 48 to close the circuit between the line wires 49 and 51 and the motor 52. The opposite side of the transformer 45 is also connected to the line wires 49 and 51. This wire 46 is also connected to the traveller 31. A shunt wire 53 extends around the relay 43 and is connected to the stop 40. There are as many relays 43 as there are rings 7, each ring being connected to its respective relay.

30 The result of this construction is that assuming that all knobs 42 are in alignment as shown in Figure 3 it is first necessary to pull out the knob 22 which will release the clutch 27 after which the button 22 may be rotated and the radio receiving set tuned to a particular station. This will move the traveller 31 and after the station has been tuned one of the relays, for instance the relay connected to the ring marked A will be moved until it is in alignment with the traveller. Another station is now tuned in and the second relay is moved until it is in alignment with the traveller. In this manner as many relays are moved as it is desired to select stations. In the present showing ten stations might be tuned and the relays set for these ten stations. The knob 22 is now moved into position to again engage the clutch 27 after which actuation of the motor 27 will impart movement to the wheels 13 and 14 and reciprocating movement to the wheel 18.

40 Assuming now that it is desired to turn on a station at a pre-determined time and assuming that that particular station is the one for which the ring A has been adjusted, it will be merely necessary to turn up into the position of Figure 9 the selector key in alignment with the time desired as shown on the clock. When the hour hand moves into contact with the arm 11 of the selector key it will complete a circuit from the hand 6 to the selector key thence to the relay 43 and through the relay 44 thus starting the motor 52. At the same time the current passing through the relay 43 will pull the armature thereof in such a manner as to move the stop 40

of this particular relay into alignment with the stop gate which is now moving toward it from either the right or the left along the tracks 32 the direction of movement depending upon the previous position of the slider. As either of the arms 36 or 37 come into contact with the stop 40 they will pivot and permit the stop to pass therebetween but at this time there will be no electrical connection between the stop 40 and the stop gate, due to the insulated pieces 38 and 39, but as soon as the stop passes one of the pivoted ends of the gate it will engage the metal portion of the gate and will complete a circuit through the shunt wire 50 around the relay 44 thus stopping the motor 52 and consequently the traveller 31. As the wheel 18 is connected to the tuning mechanism of the radio it will be evident that the amount of movement of this wheel will regulate the tuning of the set and as the respective relays have been positioned when the set was in tune with the various stations, it will be evident that when the traveller is brought to rest at a definite position the wheel 18 will be turned to the station previously selected. As the hand 6 moves out of engagement with the selector key the relay 43 will be released thus withdrawing the stop 40 and as a consequence when the hour hand reaches the next selector key the mechanism is free to operate as above described.

50 It will thus be seen that I have produced a device wherein certain stops definitely positioned may be contacted for the purpose of selecting a station and for driving the tuning mechanism until that selected station has been tuned and to then stop the mechanism so that the program may be properly received.

55 It is to be understood that the form of my invention herewith shown and described is to be taken as a preferred example of the same and that various changes relative to the material, size, shape and arrangement of parts may be resorted to without departing from the spirit of the invention or the scope of the subjoined claim.

60 Having thus described my invention, I claim:—

65 In a program selecting mechanism, a station selector including a clock having a plurality of insulated concentric metal rings positioned about said clock, a plurality of contacts carried by each of said rings, each of said contacts having an arm capable of being extended into the path of movement of an arm carried by one of the clock hands, a remotely positioned driving mechanism, a plurality of relays, each of said relays being connected to one of said concentric rings, a movable stop carried by each of said relays and adapted to be actuated thereby, said relays being adjustably positioned with respect to said driving mechanism, a slider actuated by said driving mechanism and adapted to successively pass said relays and to be stopped adjacent any of said relays when actuated, said driving mechanism being connected to a tuning apparatus whereby the stopping of said driving apparatus will position said tuning apparatus.
